(57) CLAIM

I claim the ornamental design for the pendant wave, as shown and described.

DESCRIPTION

FIG. 1 is a front perspective view of the new ornamental pendant wave of the present invention.

FIG. 2 is a front view thereof.

FIG. 3 is a back view thereof.

FIG. 4 is a left side view, of which the right side is a mirror image thereof.

FIG. 5 is a top view thereof; and,

FIG. 6 is a bottom view thereof.
